OIL SAVER

John J. Dempsey, Cleveland, Ohio

Application August 11, 1950, Serial No. 178,781.

10 Claims. (Cl. 286—16)

1

This invention relates to oil savers and co-operating apparatus associated therewith for attachment to the upper end of well casings. The invention includes an improved oil saver and an improved combination of the oil saver with a sheave support.

The oil saver of the invention is of general utility for closing the upper end of a well-casing and forming a seal around any vertical cable, rod, tube, or the like, extending downwardly into the casing and vertically movable therein. The combination of oil saver and sheave support is particularly adapted for use in connection with a flexible cable for supporting a drill, swab, or other tool, and moving it vertically in the well casing.

One object of the invention is to provide an oil saver in which the apparatus that embraces the cable, rod, or tube is horizontally adjustable to accommodate lateral displacement of the cable, rod, or tube with respect to the well casing.

Another object of the invention is to provide a combination of oil saver and sheave support for a tool supporting cable in which the cable embracing apparatus of the oil saver may be adjusted horizontally for centering it with the cable as wear on the sheave reduces its effective diameter and displaces the cable laterally with respect to the well casing.

Still another object of the invention is to provide an oil saver of simplified design that possesses the foregoing characteristics, is economical to manufacture, and convenient to use.

A characteristic feature of the invention is the employment of a base member adapted to be mounted on the upper end of a well casing and a mechanism for embracing the cable, rod, or tube that is horizontally slidable on the base member for centering with respect to the cable, rod, or tube, and means mounted on the base member that is operative to clamp the embracing mechanism on the base member in its centered position.

Still other objects, advantages, and features of the invention will become apparent from the following detailed description of a preferred illustrative embodiment of the invention as employed in association with a flexible tool supporting cable passing partially around a sheave, and downwardly into the well casing.

In the drawing

Figure 1 is a side elevation of an oil saver and associated sheave support mounted on the upper end of a well casing;

Fig. 2 is an end elevation of the structure shown in Fig. 1;

Fig. 3 is a plan view on an enlarged scale of the oil saver shown in Fig. 1;

2

Fig. 4 is a vertical sectional view of the oil saver on the same scale as Fig. 3, the plane of the section being indicated by the line 4—4 in Fig. 1;

Fig. 5 is another vertical sectional view of the oil saver on the same scale as Fig. 3, the plane of section being indicated by the line 5—5 in Fig. 4; and

Fig. 6 is a side elevation of the oil saver, similar to Fig. 2, but on the scale of Fig. 3 and showing the oil saver with parts thereof in different positions.

Referring first to Figures 1 and 2, a sheave support adapted for use in accordance with the present invention may comprise an internally threaded tubular base member 10 adapted to be threaded over the open upper end of a conventional well casing 11. A sheave supporting arm 12 may be welded, or otherwise rigidly secured, to the tubular base member 10 and extend upwardly at one side thereof for carrying a sheave 13 at its upper end. The sheave 13 may be pivotally mounted on the upwardly extending arm 12 by means of a shaft 14 mounted at its opposite ends for rotation in the free ends of a pair of pivot arms 16. The arms 16 may be pivotally mounted at their opposite ends on the upper end of the arm 12 by means of a shaft 17 extending therethrough. The arm 12 is preferably shaped at its upper end to form a yoke having a pair of spaced arms 18 straddling the sheave 13 and disposed inwardly of the arms 16 for supporting the sheave shaft 14.

The shape and dimensions of the sheave supporting arm 12 and the diameter of the sheave 13 are selected so that a cable 20, passing over the sheave and downwardly therefrom, will be guided vertically downwardly into the casing 11 substantially on the axis thereof. By pivotally mounting the sheave 13 on the pivot arms 16, in the manner described, the sheave may be swung upwardly and to one side in a counter-clockwise direction, as viewed in Fig. 1, in order to provide adequate clearance for the insertion of tools into the casing 11 and for withdrawing them from the casing.

Referring also to Figures 3 to 5, the oil saver shown in the drawing may comprise a tubular base member 21 having its lower end threaded for mounting within the upper end of the base 10 of the sheave support. The upper end of the base member 21 of the oil saver is preferably provided with an outwardly extending flange 22 that provides a flat annular upper surface 23 surrounding the bore of the base member. The surface 23 is preferably provided with an annular groove 24 for receiving an annular gasket 26 upon which other parts of the oil saver may freely slide,

as hereinafter described, and for sealing the juncture of the flange 22 and said other parts. The gasket 24 may suitably be made of a relative soft metal, such as lead, Babbitt metal, or the like.

The upper end of the tubular base member 21 of the oil saver may be partially closed by a pair of plates 27 and 28, each of which may conveniently have the shape of a half disc. The plates 27 and 28 slidably rest upon the gasket 26 and together form a disc-shaped cover divided into two parts along a diameter thereof. The adjacent edges of the plates that are engaged to form this cover are provided with complementary notches 29 normally positioned in registry to form a cylindrical opening through the cover adapted to accommodate the cable 20.

When the plates 27 and 28 are brought together with the notches 29 in registry, the plates are guided by suitable means, such as a pair of dowel pins 31 mounted in the plate 28 and dowel holes 32 formed in the opposite plate 27.

A pair of lips 33 and 34 are respectively formed on the plates 27 and 28 so as to project beyond the meeting edges of these plates at opposite sides of the notches 29 therein, the lip on each plate being adapted to overlie a portion of the opposite plate when the plates are slid together into notch registering relation. The lips 33 and 34 may also be formed of metal plates, suitably having the shape of disc segments with one-half of each segment overlying and being welded, or otherwise secured, to the upper surface of the associated plate 27 or 28.

A pair of packing holders 37 and 38 respectively mounted on the plates 27 and 28 in any suitable manner, as by welding. Each of the packing holders may conveniently be formed from a plate bent to a U-shape and having the ends of its legs welded to the associated plate 27 or 28 on opposite sides of the notches 29 therein. This housing structure is left open along the end adjacent the notch 29 and is closed along its opposite end by a plate 39 having an enlarged boss 40 formed therein, the closure plates 39 being conveniently welded to the U-shaped portions of the packing housings. The U-shaped plates 39 are both notched at 44 to provide an upper cable receiving aperture aligned with the aperture formed by the notches 29 in the plates 27 and 28.

The bosses 40 on the packing housing closure plates 39 are drilled and tapped to receive suitable adjusting bolts 41 that project through the bosses into the packing housings. On the ends of the bolts 41 within the packing housings, blocks 42 are rotatably mounted for engaging suitable packing elements 43 of rubber, impregnated fibrous material, or the like. As best shown in Fig. 4, rotation of the bolts 41 to move the blocks 42 toward each other, forces the packing elements 43 against opposite sides of the cable 20 with an adjustable pressure, thus providing a seal against the passage of liquids and gases upwardly through the notches 29 around the cable 20. This requires that the plates 27 and 28 and the packing holders 37 and 38 mounted thereon be held firmly together. For this purpose a generally U-shaped clamp 46 having elongated slots 47 in the legs thereof is pivotally mounted on one of the packing holders 37 by means of suitable pins or lugs 48 formed on the sides of the packing holder 37 and projecting through the slots 47 of the clamp. The closed end of the U-shaped clamp is drilled and tapped to receive a setscrew 49 adapted to bear against the packing holder 37, and the ends of the legs of the clamp 46 are

provided with notches 51 adapted to fit over a pin 52 welded onto the other packing holder 38 below the boss 39 thereon. The legs of the clamp 46 are preferably curved at 53 to dispose the setscrew 49 far enough above the adjacent bolt 41 to permit both to be readily adjusted by means of a wrench without undue interference.

As best shown in Figures 2 and 4, the notches 51 in the legs of the clamp 46 are adapted to receive the opposite ends of the pin 52, and tightening of the setscrew 49 against the packing holder 37 draws the plates 27 and 28 and packing holders 37 and 38 tightly together.

A pair of identical clamps 56 are respectively secured in diametrically opposite positions to the sides of the base member 21 of the oil saver for clamping the slideably mounted plates 27 and 28 against movement after they have been locked together by means of the clamp 46. The clamps 56 may conveniently comprise U-shaped brackets having one leg welded to the underside of the flange 22. The other legs of the U-shaped members project inwardly and may be provided with enlarged bosses 57 drilled and tapped to receive setscrews 58. Tightening of the setscrews 58 exerts downward forces on the lips 33 and 34 of the plates 27 and 28 and holds them firmly against the gasket 26.

The use of the apparatus described above may be illustrated as applied to the swabbing of a gas well. Before the swab (not shown) is lowered into the well casing, the sheave support is mounted on the upper end of the casing, and the oil saver is secured in place by threading it into the upper end of the base 10 of the sheave support. The setscrews 58 on the brackets 56 are loosened, the clamp 46 is released from the pin 52, and the plates 27 and 28 and the associated packing holders 37 and 38 are separated and removed from the oil saver by sliding them apart in the directions indicated by arrows in Fig. 6. The swab is attached to the end of the cable 20 and is passed downwardly through the base member 21 of the oil saver, through the base 10 of the sheave support, and into the casing, where it is suspended by the cable 20 passing over the sheave 13 to a suitable power driven reel (not shown).

At this point, if desired, the plates 27 and 28 may be replaced on the oil saver loosely in the positions shown in Fig. 6 and rest there as the cable 20 is paid out to lower the swab into the well. However, the plates 27 and 28 may be replaced on the oil saver at any time after insertion of the swab into the casing and before danger of a blow-off during raising of the swab from the well. Depending upon the well conditions, the swab may be raised a considerable distance from the bottom of the well before it becomes necessary to move and lock the plates 27 and 28 together and to adjust the packing elements 43 tightly against the cable by means of the packing bolts 41.

After the packing elements 43 have thus been set tightly against the cable, the setscrews 58 are tightened to hold the plates 27 and 28 against the gasket 26 with the associated packing structure in perfect alignment with the vertical path of travel of the cable 20. Thus, if the vertical path of travel of the cable is not centered perfectly on the axis of the well casing on which the oil saver is mounted because of wear on the sheave 13 or misalignment from other causes, the lateral positions of the plates 27 and 28 and the packing structure carried thereby will automatically be centered with respect to the cable and

will be clamped and held in the centered position by the setscrews 58.

As raising of the swab is continued, the oil saver provides a reliable closure at the top of the well casing that is sealed tightly around the cable for preventing a blow-off of gases or liquids from the well and for preventing the swab from being forcefully ejected from the well with danger to the operators and surrounding buildings and machinery.

When the swab has been raised to the upper end of the well casing, it may be removed after the setscrews 58 have been loosened and the clamp 46 has been removed from the pin 52 to permit the plates 27 and 28 again to be withdrawn and removed in the directions indicated in Figure 6.

From the foregoing description of a preferred embodiment of the invention and the manner in which it is employed in practice, it will be apparent that I have provided a simple and inexpensive oil saver and sheave supporting structure in which the packing structure of the oil saver is self adjusting horizontally, in the normal course of its use, to accommodate lateral displacement or misalignment of a cable, rod, tube, or the like, extending downwardly therethrough. The rugged character of the structure and the simplicity of its operation contribute to make it a highly useful, safe, and economical apparatus for performing the protective functions for which it is intended.

It will also be apparent that the particular structure shown and described for illustrative purposes may be varied in numerous respects without departing from the true scope of the invention, as defined in the appended claims. While the use of the invention has been illustrated particularly with reference to the swabbing of a well, it will be understood that the invention is equally useful in numerous other operations in which a flexible cable or wire, or a rigid rod, hollow tube, or the like, is extended downwardly into a well casing for vertical movement therein and it is desired to seal the upper end of the casing against the escape of gases, liquids, or both.

Having described my invention, I claim:

1. An oil saver comprising a tubular base member having a lower end for attachment to a well casing and a flat annular upper surface surrounding the bore thereof, a pair of closure plates slideably supported on said surface, said plates having adjacent horizontally aligned edges adapted to be engaged when said plates are slid together along said surface to form a cover substantially closing said bore, a vertical passage through said cover formed by registering notches in the adjacent horizontally aligned edges of said plates, cooperating guide means carried by said plates for guiding them into notch registering relation when they are slide together along said surface, a pair of lips disposed on opposite sides of the vertical passage defined by said notches, each of said lips being rigidly secured to one of said plates and overlying the other when the plates are slid together into notch registering relation, an adjustable clamp mounted on one of said plates and cooperating means mounted on the other of said plates for drawing the plates together into notch registering relation while the plates are slideable together along said surface, and means operatively mounted on said base member for applying forces downwardly on said lips to clamp said plates in bore closing relation toward said surface with the registered notches.

aligned with the axis of said bore or laterally offset therefrom.

2. An oil saver comprising a tubular base member having a lower end for attachment to a well casing and a flat annular upper surface surrounding the bore thereof, a pair of closure plates slideably supported on said surface, said plates having adjacent edges adapted to be engaged when said plates are slid together along said surface to form a cover substantially closing said bore, a vertical passage through said cover formed by registering notches in the adjacent edges of said plates, cooperating guide means on said plates for guiding them into notch registering relation when they are slid together along said surface, a pair of lips respectively formed on said plates and projecting beyond the meeting edges thereof on opposite sides of the notches therein, the lip on each plate overlying a portion of the other plate when the plates are slid together into notch registering relation, a pair of packing holders respectively mounted on said plates for embracing opposite sides of a vertical cable extending downwardly through said hole when said plates are slid together in notch registering relation, and means operatively mounted on said base member for applying forces downwardly on said lips to clamp said plates in bore closing relation toward said surface with said notches in registry.

3. An oil saver comprising a tubular base member having a lower end for attachment to a well casing and a flat annular upper surface surrounding the bore thereof, a pair of closure plates slideably supported on said surface, said plates having adjacent edges adapted to be engaged when said plates are slid together along said surface to form a cover substantially closing said bore, a vertical passage through said cover formed by registering notches in the adjacent edges of said plates, cooperating guide means on said plates for guiding them into notch registering relation when they are slid together along said surface, a pair of lips respectively formed on said plates and projecting beyond the meeting edges thereof on opposite sides of the notches therein, the lip on each plate overlying a portion of the other plate when the plates are slid together into notch registering relation, a pair of packing holders respectively mounted on said plates for embracing opposite sides of a vertical cable extending downwardly through said hole when said plates are slid together in notch registering relation, an adjustable clamp mounted on one of said plates and clamp engaging means mounted on the other of said plates for coaction to draw the adjacent edges of said plates together without restricting them from sliding together along said surface, and means operatively mounted on the upper end of said base member for applying forces downwardly on said lips to clamp said plates in bore closing relation toward said surface.

4. In combination, a well casing, a sheave support mounted on the upper open end of said casing, a sheave rotatably mounted on the upper end of said sheave support for guiding a cable generally axially into said casing, and an oil saver comprising a tubular base member mounted over the upper open end of said casing and having a flat annular upper surface surrounding the bore thereof, a pair of closure plates slideably supported on said surface, said plates having adjacent horizontally aligned edges adapted to be engaged when said plates are slid together along said surface to form a cover substantially clos-

ing said bore, a vertical passage through said cover formed by registering notches in the adjacent horizontally aligned edges of said plates and adapted to receive said cable, cooperating guide means carried by said plates for guiding them into notch registering relation when they are slid together along said surface, a pair of plate lips disposed on opposite sides of the vertical passage defined by said notches, each of said lips being rigidly secured to one of said plates and overlying the other when the plates are slid together into notch registering relation, an adjustable clamp mounted on one of said plates and cooperating means mounted on the other of said plates for drawing the plates together into notch registering relation while the plates are slideable together along said surface, and means operatively mounted on said base member for applying force downwardly on said lips to clamp said plates in bore closing relation toward said surface with the registered notches disposed at a selected position on the axis of or offset from the axis of said bore.

5. In combination, a sheave support comprising a tubular fitting for mounting on the upper open end of a well casing, an upwardly extending arm mounted on said fitting, and a sheave rotatably mounted on said arm for guiding a cable generally axially into said fitting and an oil saver comprising a tubular base member having a lower end mounted on said fitting coaxially therewith and having a flat annular upper surface surrounding the bore thereof, a pair of closure plates slideably supported in side by side relation on said surface, said plates having adjacent edges adapted to be engaged when said plates are slid together along said surface to form a cover substantially closing said bore, a vertical passage through said cover formed by registering notches in the adjacent edges of said plates and adapted to receive said cable, cooperating guide means carried by said plates for guiding them into notch registering relation when they are slid together along said surface, a pair of lips respectively formed on said plates and projecting beyond the meeting edges thereof on opposite sides of the notches therein, the lip on each plate overlying a portion of the other plate when the plates are slid together into notch registering relation, an adjustable clamp mounted on one of said plates and cooperating means mounted on the other of said plates for drawing the plates together into notch registering relation independently of their location and orientation on said surface, and means operatively mounted on said base member for applying force downwardly on said lips to clamp said plates in bore closing relation toward said surface with the registered notches disposed at a selected position on the axis of or offset laterally in any direction from the axis of said bore.

6. In combination, a sheave support comprising a tubular fitting for mounting on the upper open end of a well casing, an upwardly extending arm mounted on said fitting, and a sheave rotatably mounted on said arm for guiding a cable generally axially into said fitting and an oil saver comprising a tubular base member having a lower end mounted on said fitting coaxially therewith and having a flat annular upper surface sur-

rounding the bore thereof, a pair of closure plates slideably supported on said surface for movement in any direction parallel thereto, said plates having adjacent edges adapted to be engaged when said plates are slid together along said surface to form a cover substantially closing said bore, a vertical passage through said cover formed by registering notches in the adjacent edges of said plates and adapted to receive said cable, cooperating guide means carried by said plates for guiding them into notch registering relation when they are slid together along said surface independently of their location and orientation on said surface, a pair of lips respectively formed on said plates and projecting beyond the meeting edges thereof on opposite sides of the notches therein, the lip on each plate overlying a portion of the other plate when the plates are slid together into notch registering relation, a pair of packing holders respectively mounted on said plates for embracing opposite sides of a vertical cable extending downwardly through said hole when said plates are slid together in notch registering relation, and means operatively mounted on said base member for clamping said plates in bore closing relation toward said surface with said notches in registry.

7. The apparatus of claim 6 including an adjustable clamp mounted on one of said plates and cooperating means mounted on the other of said plates for drawing the plates together in notch registering relation while the plates are slideable together along said surface.

8. The apparatus of claim 1 in which said adjustable clamp and cooperating means are respectively freely movable with and carried by the plates on which they are respectively mounted, whereby said plates may be drawn together in notch registering relation irrespective of their position on said annular upper surface.

9. The apparatus of claim 2 including an adjustable clamp mounted on one of said plates for movement therewith and cooperative means mounted on the other of said plates for movement therewith and engageable by said clamp for drawing the plates together in notch registering relation independently of the location and orientation of said plates on said annular upper surface.

10. The apparatus of claim 3 in which said adjustable clamp and cooperating means are respectively freely movable with and carried entirely by the plates on which they are respectively mounted, whereby said plates may be drawn together in notch registering relation irrespective of their position on said annular upper surface.

JOHN J. DEMPSEY.
